GARMENT RACK

Oscar H. Ogren, Rockford, Ill.

Application August 9, 1940, Serial No. 351,923

8 Claims. (Cl. 211—100)

My invention relates to improvements in folding garment hangers.

The principal object of my invention is to provide a clothes hanger suitable for supporting a number of conventional hangers containing garments, and adapted to fold upwardly to a closed position in order to reduce to a minimum the space occupied by the clothes and garment hanger, making the device especially useful when employed in a limited amount of space such as a shallow closet or on the inside of a door thereof.

Another object of the invention is to provide a device of this type of such design that it will firmly support a quantity of garments and yet is of relatively light weight construction to reduce cost of manufacture, and to permit simple and ready installation.

A further object of the invention is to provide a device as described which, when in the open position, enables the user readily and easily to select, hang, and remove garments through the provision on the hanger arm of a plurality of spaced vertical pins which permit sliding of the hangers therebetween, thereby eliminating the crowding and mussing encountered where the hangers are held in a fixed position on a hanger arm supporting a comparable quantity of garments.

Still another object of the invention is to provide a pole depending from the free end of the hanger arm for more conveniently raising the said arm to the closed position, and for disengaging it therefrom.

Another object of the improvements is the provision of horizontal latch bar extending outwardly from the wall or door on which the device is mounted, so as to be always visible to the user. Thus, when folding the hanger arm to the closed position, the said arm can be easily latched to the bar, notwithstanding any lateral swing of the hanger arm that might misalign it in its upward arc.

Figure 1 is a side elevation of the device in the open position, showing a hanger suspended therefrom and the assist pole in the dotted position it assumes in order to avoid limiting any bulging of the garments on a crowded hanger arm;

Fig. 2 is a side elevation of the device in the closed position, the dotted position of the assist pole being the one at which it disengages the hanger arm for return to the open position;

Fig. 3 is a top elevation on the line 3—3 of Fig. 2;

Fig. 4 is a vertical section on the line 4—4 of Fig. 3.

A hanger arm 5 having a crowned top is pivotally mounted at one end on a pin 6 so as to swing in a vertical plane within a bracket 7, having semi-circular flanges, which is fastened to a wall or door 8 by screws 9.

A plurality of pins 10 are spaced along the top side of the arm 5 at right angles thereto and are secured thereon by a suitable method.

A U-shaped piece 11 is adapted to straddle the arm 5 diagonally near its free end 5a and is secured thereto by a rivet 12. A bar 13 having an obliquely bent lower end is fastened to the top crosspiece of the U-shaped piece 11 by fixing a bolt 14 through suitable bores.

15 A pole 15 is suspended from the lower sides of the piece 11 and is adapted to swivel therein on a pivot formed by a bolt 16, which is mounted in the curled back portion of a plate 17 secured to the pole 15 by screws 18. A right angled slot 19 is provided in the sides of piece 11 to permit a top end 20 of the pole 15 to locate itself more closely to the free end 5a of the arm 5, as will be hereinafter described.

25 A chain 21 is secured at its lower end to the bar 13 while at its upper end is anchored to a bracket 22 that is secured to a wall, or the door 8, by screws 23 in vertical alignment with the bracket 7 and spaced therefrom so that the chain 21 is taut when the arm 5 has assumed a horizontal position. The provision of a bar 13 as a diagonal support complementing the chain 21 positions the chain 21 as illustrated in Fig. 2, when the hanger arm 5 is in the closed position. This spaces the chain 21 from hanger arm 5 so that 30 it will not drape about clothes hung therefrom, nor interfere with the operation of the hanger arm 5.

The bracket 22 has an outwardly projecting top piece 24, fashioned at its outer portion 24a to form a rectangular opening 25. As is apparent from Figs. 1 and 3, this bracket 22 is a one-piece bar, shaped as illustrated, the top end being turned back to form the opening 25 and then faced against itself and secured in this position 40 by rivets 26. One side of the opening 25 is bent through 90 degrees as shown at 22a and 22b to provide a lip 27 against which the end 20 of the pole 15 is pressed by rotation thereof through the dotted line position of Fig. 2 to release the arm 5 from the closed position.

45 The end of this rotation occurs when the end of the pole 15 abuts directly against the bottom side of the arm 5 with the bolt 16 in the short arm of the angled slot 19. This causes the pole 50 15 to become in effect a combination of the arm 55

5 to assist the operator in raising and lowering the arm 5.

Clothes hangers of the conventional sort are designated by number 28. Spare hangers may be hung from bracket 22, as illustrated in Figure 1.

In operation, the user places the hangers 28 containing garments on the arm 5, spacing them along the arm by the pins 10. It is significant to note that the spaced pins 10 permit limited sliding of the clothes hangers 28 along the arm 5, thereby making it easier to select clothes or to hang and remove them from the arm 5, since crowding and bunching is largely eliminated. Having done this and wishing to close the closet door, if it be such, the operator grasps the pole 15 and pushes the arm 5 and suspended garments upwardly toward the position illustrated in Fig. 2. When the diagonally cut end 5a of arm 5 contacts the lip 27, it flexes the bracket piece 24 upwardly until the end 5a enters the opening 25, whereupon the piece 24 returns to its horizontal position, locking the arm 5 in this upward position. During this upward movement, the hangers 28 are limited in sliding along the arm 5 by the pegs 10 and are maintained in a vertical position by gravity, the attached garments assuming a like position.

To release the garment hanger from the closed position, the user merely grasps the pole 15 and swings it outwardly to the dotted position in Fig. 2. This causes the end 20 of the pole 15 to bear against the lip 27 forcing the bracket piece 24 upwardly to release the arm 5 therefrom, permitting it to be lowered to the horizontal position, as in Figure 1. Thus, it is clear that regardless of the height of the user, he may readily raise or lower the arm 5 by the pole 15. The fact that the bracket piece 24 is designed to project a considerable distance from the wall or door 8 makes it visible at all times to permit accurate alignment of the arm 5 and bracket piece 24 in the upward arc of the former, notwithstanding any lateral movement in the arm 5. It is evident that this arrangement contributes to the ease with which the end 5a of the arm 5 may be locked within the opening 25.

The slots 19 in the bracket 11 permit the end 20 of the pole 15 to drop a corresponding distance from the arm 5 so that the pole may be swung outwardly, as in the dotted line position in Figure 1, to avoid limiting the bulging of the garments when the hanger is crowded to capacity.

I claim:

1. In a clothes hanger, a hanger arm having mounting means at one end and pivotally mounted at this end to permit hinged movement in a vertical plane, flexible support means fixed at one end above the said mounting means of the hanger arm, the other end being attached to substantially the free end of the hanger arm, the said flexible means limiting downward movement of the said hanger arm to a horizontal position, a plurality of pins spaced along the hanger arm permitting sliding of the hangers therebetween, an outwardly projecting horizontal bar positioned above the said mounting means of the hanger arm, the free end of the said bar being adapted to engage the free end of the hanger arm at a point less than vertical in its upward arc, manual means for disengaging the said bar from the free end of the hanger arm, permitting the latter to return to a horizontal position.

2. In a clothes hanger, a hanger arm having mounting means at one end and pivotally mounted at this end to permit hinged movement in a vertical plane,

vertical plane, a plurality of pins spaced along the hanger arm permitting sliding of the hangers therebetween, a U-shaped bracket comprising upper and lower forks in vertical alignment with the said mounting means of the hanger arm, the said upper fork projecting outwardly a substantial distance, flexible support means fixed at one end to the lower fork of the said U-shaped bracket, the other end being attached to substantially the free end of the hanger arm, the said flexible means limiting downward movement of the said hanger arm to a horizontal position, a loop in the outward end of the said upper fork for reception of the free end of the said hanger arm and to provide a latch therefor, a pole pivotally mounted to the free end of the hanger arm to swing in a vertical plane, rotatable to release the latch.

3. In a clothes hanger, a hanger arm having mounting means at one end and pivotally mounted at this end to permit hinged movement in a vertical plane, a plurality of pins spaced along the hanger arm permitting sliding of the hangers therebetween, flexible support means, one end of which is attached to substantially the free end of the hanger arm, the other end being fixed above the said mounting means of the hanger arm, the said flexible means limiting downward movement of the said hanger arm to a horizontal position, an outwardly projecting horizontal spring-bar positioned above the said mounting means of the hanger arm, a loop in the outward end of the said spring-bar for reception of the free end of the said hanger arm and to provide a latch therefor, a pole pivotally mounted to the free end of the hanger arm to swing in a vertical plane therewith, the top of the said pole being spaced from the free end of the said hanger arm to release the hanger arm from the said loop upon being swung outwardly.

4. In a clothes hanger, a hanger arm having mounting means at one end and pivotally mounted at this end to permit hinged movement in a vertical plane, a plurality of pins spaced along the hanger arm permitting sliding of the hangers therebetween, support means having one end attached to substantially the free end of the hanger arm, the other end being fixed above the said mounting means of the hanger arm and limiting downward movement of the said hanger arm to a horizontal position, the said support means consisting of a rigid rod, the lower end of which is attached to the free end of the hanger arm, and a complementary flexible member extending from the upper end of the rigid rod, the rigid rod and flexible means being so proportioned as to length that the flexible means hangs clear of the hanger arm in any position in its upward movement, an outwardly projecting horizontal spring-bar positioned above the said mounting means of the hanger arm, a loop in the outward end of the said spring-bar for reception of the free end of the said hanger arm and to provide a latch therefor, a pole pivotally mounted to the free end of the hanger arm to swing in a vertical plane therewith, the top of the said pole being spaced from the free end of the said hanger arm to release the hanger arm from the said loop upon being swung outwardly.

5. In a clothes hanger, a hanger arm having mounting means at one end and pivotally mounted at this end to permit hinged movement in a vertical plane, support means having one end attached to substantially the free end of the hanger arm, the other end being fixed above the

said mounting means of the hanger arm and limiting downward movement of the said hanger arm to a horizontal position, the said support means consisting of a rigid rod, the lower end of which is attached to the free end of the hanger arm, and a complementary flexible member extending from the upper end of the rigid rod, the rigid rod and flexible means being so proportioned as to length that the flexible means hangs clear of the hanger arm in any position in its upward movement, a plurality of pins spaced along the hanger arm permitting sliding of the hangers therebetween, an outwardly projecting horizontal bar positioned above the said mounting means of the hanger arm, the free end of the said bar being adapted to engage the free end of the hanger arm at a point less than vertical in its upward arc, manual means for disengaging the said bar from the free end of the hanger arm, permitting the latter to return to a horizontal position.

6. In a latch mechanism, the combination of a swingably mounted arm, a spring bar fixed to a support means, a loop in the outward end of the said spring bar for reception of an end of the said arm providing a latch therefor, a rod pivotally mounted to the latch end of the said arm to swing in the same plane therewith, the top of the said rod being spaced from the said loop in the spring bar and adapted to bear against the said loop to release the arm therefrom upon being swung outwardly.

7. In a clothes hanger, a hanger arm having mounting means at one end and pivotally mounted at this end to permit hinged movement in a vertical plane, a plurality of pins spaced along the hanger arm permitting sliding of the hangers therebetween, flexible support means, one end of which is attached to substantially the free end of the hanger arm, the other end being fixed above the said mounting means of the hanger arm, the said flexible means limiting downward movement

of the said hanger arm to a horizontal position, an outwardly projecting horizontal spring bar positioned above the said mounting means of the hanger arm, a loop in the outward end of the said spring bar for reception of the free end of the said hanger arm and to provide a latch therefor, a pole pivotally mounted to the free end of the hanger arm to swing in a vertical plane therewith, the top of the said pole being spaced from the free end of the said hanger arm to release the hanger arm from the said loop upon being swung outwardly, the top of the said pole being adapted to abut the said hanger arm when swung outwardly to assist in raising and lowering the said hanger arm.

8. In a clothes hanger, a hanger arm having mounting means at one end and pivotally mounted at this end to permit hinged movement in a vertical plane, a plurality of pins spaced along the hanger arm permitting sliding of the hangers therebetween, a U-shaped bracket comprising upper and lower forks in vertical alignment with the said mounting means mounted above the said mounting means of the hanger arm, the said upper fork projecting outwardly a substantial distance, flexible support means fixed at one end to the lower fork of the said U-shaped bracket, the other end being attached to substantially the free end of the hanger arm, the said flexible means limiting downward movement of the said hanger arm to a horizontal position, a loop in the outward end of the said upper fork for reception of the free end of the said hanger arm and to provide a latch therefor, a pole pivotally mounted to the free end of the hanger arm to swing in a vertical plane, rotatable to release the latch, the top of said pole being adapted to abut the said hanger arm upon being swung outwardly after release of the latch to assist in raising and lowering the said hanger arm.

OSCAR H. OGREN.
